UNITED STATES PATENT OFFICE.

NILS GERHARD LINDBORG, OF NEW YORK, N. Y.

PROCESS AND ARRANGEMENT FOR TREATING HYDROCARBONS, METALS, AND OTHER BODIES.

Application filed June 4, 1921, Serial No. 475,124. Renewed April 12, 1924.

To all whom it may concern:

Be it known that I, NILS GERHARD LINDBORG, engineer, subject of the King of Sweden, residing at 1990 Seventh Avenue, city, county, and State of New York, U. S. A., have invented certain new and useful Improvements in Processes and Arrangements for Treating Hydrocarbons, Metals, and Other Bodies, of which the following

10 is a specification.

The present invention relates to a process of and an apparatus for producing and treating hydrocarbons and other bodies.

In order that the invention may be clearly 15 understood reference is made to the accompanying drawings in which—

Fig. 1 is an elevation partly in section of an embodiment of the invention and

Fig. 2 is a sectional elevation of a second embodiment of the invention.

The embodiment according to Fig. 1 is particularly adapted for producing and treating hydrocarbons. That part of the apparatus, however in which the hydrocarbons produced are treated, may however also be used for treating other materials.

With reference to Fig. 1 the material to be treated, for instance pit coal, is introduced into the feed funnel 1 and is fed by means 30 of the screw conveyor 2 into the top part of the furnace chamber 3. In this chamber there are a plurality of shelves 4, 5 placed below each other, one series 4 of said shelves being attached to the furnace wall while 35 the other series 5 of shelves are attached to the central rotary shaft 6. The material is delivered by the conveyor 2 to the top shelves, and by means of the brushes 7, which are carried at the ends of arms 15 at- 40 tached to the shaft, the material is swept down on to the shelves below. Hydrocarbon gases are generated during the passage of the material down through the furnace chamber the heat of which successively increases downwards.

The side walls 8 of the furnace are surrounded by masonry 9, having a series of annular channels 10 extending round the furnace and communicating with each other, 50 so as to form a continuous passage for a suitable heating medium such as the combustion gases from a fire or furnace.

The combustion gases from the fire enter at the lower end of the masonry through

the pipe 11, flow successively through the 55 annular channels 10 and escape finally through the pipe 12. As the gases in their hottest state thus pass along the lower part of the masonry surrounding the furnace, the furnace chamber will, of course, be heated in such a manner that the heat thereof increases downwardly. In order to further increase the heat in the furnace and also in such a manner that the temperature of it increases downwardly there is arranged below 60 the furnace which is open at the bottom, an electric heating arrangement comprising a crucible 13, containing iron or other suitable metal (for instance waste iron) and into which two electrodes enter. The crucible is considerably smaller than the bottom opening of the furnace chamber and is arranged directly below the shaft 6, so that the material falling from the furnace falls 65 down at the sides of the crucible.

The hydrocarbon gases or vapors generated in the furnace are led out from the furnace at several points located at different heights. In the embodiment shown there are three outlet pipes 16, 17, 18, each 70 being provided with a cock 19. The gases or vapors from these pipes enter a common collecting pipe 20, and pass through this pipe into the receiver 21. In this receiver, which is heated in any suitable manner to the desired extent, the gases or vapors may be exposed to the reaction of reducing or oxidizing materials or may be mixed with other gases or with materials 75 in a finely divided state. 22 indicates the 80 inlet pipe for these materials.

From the receiver 21 the gases flow to a receiver 23, containing means for producing electric waves comprising two electrodes connected to an electric high tension circuit, 85 one of said electrodes consisting of a single bar 24 and the other of a rotary shaft 25 provided with a number of transverse arms 26 having pointed ends or being preferably 90 in the form of wires. When the shaft 25 rotates the ends or points of the arms 26 will continuously move to and from the stationary electrode 24, so that electric waves of a certain shape are produced, to the action of which waves the gas or the 95 vapor in the receiver is exposed.

The means for producing the waves may 100 of course be constructed in any other suit-

able manner, but preferably both the electrodes are mounted so that they may be rotated as is shown in Fig. 2.

One of the electrodes is suitably provided with a condenser 27 of a suitable capacity. The treatment of the gas or the vapor with electricity may also be effected by leading electrically charged particles through it.

The resulting compounds are withdrawn from the receiver through the outlet pipe 28.

It is evident that the gases brought into the mixing receiver 21 may consist of a mixture of different hydrocarbon gases or vapors.

According to the embodiment shown in Fig. 2, the chamber in which the treatment by means of electric high tension current takes place, is arranged within the mixing receiver 21, into which the materials to be treated first enter through the pipe 20. Said chamber is formed of a cylindrical (or otherwise shaped) covering 23 of an electric non-conductor and of such an outer diameter that a space of suitable size is formed between the inner cover 23 and the wall of the receiver 21, through which space the materials pass before entering into the space enclosed by the inner cover 23. Such inner space is closed at the top but communicates at the bottom with the interior of the receiver 21. The receiver 21 is suitably surrounded by an outer covering 30 in which a suitable heating medium is allowed to circulate for heating the receiver 21.

The electrodes arranged in the inner cover consist of a central rotary shaft 25, provided with a number of suitably pointed transverse arms 26 preferably of wire and a condenser 27 similarly to the rotary electrode of the first embodiment, and of a rotary fork-shaped member 31, the stem of which forms a supporting shaft which projects through the bottom of the apparatus below and which is in driving connection by means of a worm-gear with a driving shaft 32.

The branches of the fork extend along the inside of the inner cover and are in contact therewith or nearly so. In the bottom part of the apparatus there is arranged a screw conveyor 33 the outer end of which extends into a discharging cover or pipe 34, which is provided with a discharging hole 35.

The materials to be treated enter through the pipe 20 into the upper portion of the space between the wall of the receiver 21 and the inner cover, then pass down this space during which passage they are heated and, if desired, mixed with other gases, with which they may chemically react. They then enter into the space enclosed by the inner cover 23 at bottom part thereof and flow upwards through this space to the outlet 28. During the last-mentioned

stage of their motion the materials are exposed to the electric action of the high tension current.

On the inside of the inner cover some solid or viscous semi-fluid particles are deposited which are produced by the reaction.

These particles are removed from the inside of such cover action due to the rotation of the branches of the electrode 31, so that they fall down to the bottom of the apparatus from which they are continuously removed by means of the screw conveyor 35.

The fork may, if desired, be replaced by any other arrangement whereby the inside of the cover 23 may be cleared of the deposits.

The process in the apparatus should take place at vacuum or low pressure and the pressure or vacuum is selected with regard to the products desired, different products being obtained according as pressure is greater or less or vacuum is used. It may in certain cases be necessary that the materials are treated successively in two or more apparatus arranged in series.

It has been found that it is not essential that the compounds to be treated in the aforesaid manner should be gaseous or vaporous, but solid or liquid bodies or mixtures of solid and liquid bodies may be treated, particularly certain metals, for instance aluminum, mixed with hydrocarbons. The solid or liquid body should be in a finely divided state that is pulverized.

The proportions of the materials mixed in the receiver 21, and also the voltage between the electrodes and the speed at which such electrodes are driven are adjusted in accordance with the products which it is desired to obtain. In practice, the speed at which the electrodes have been driven has varied between 3000-7000 revolutions per minute, though good results could probably be obtained by speeds outside this range.

Owing to the relative high speed between the two electrodes and owing to the special construction of the electrodes the interior of the chamber during the rotation of the electrodes will be in a state of electrical tension, the pressure of course at different parts varying as the electrodes rotate, such pressures varying substantially in accordance with a sine curve, and it is believed that such tension acting upon the hydrocarbons or other materials has the effect of breaking up the molecules of the hydrocarbon and detaching therefrom certain ions which combine with other ions in statu nascendi. The waves of electrical pressure thus produced have a different effect upon the gases or the like than would be obtained if the machine were designed to obtain a

series of electric sparks between the two electrodes.

As previously mentioned the apparatus is not limited to use with hydrocarbons, but 5 as an example of the action of the apparatus upon hydrocarbons it can be stated that when kerosene in a gasous state is passed through the device a high percentage of gasoline is obtained together with tar 10 products, petroleum ether and gas.

Other hydrocarbons can be treated with advantageous effect, such as methyl alcohol, from which can be obtained an aldehyde and acetic acid. Also, if desired, the hydro- 15 carbons may be mixed in the mixing chamber with hydrogen or oxygen so that a reducing or oxydizing effect may be obtained. The proportions of the gases and the kind, 20 will of course depend upon the resultant product which it is desired to obtain.

Also metals in a pulverized state may be treated with or without hydrocarbons.

Having now particularly described and ascertained the nature of my said invention 25 and in what manner the same is to be performed, I declare that what I claim is:—

1. The process of treating materials in a gaseous or finely divided state which consists in submitting such materials to the 30 action of high tension electricity in a receiver in which a pair of electrodes are moved relatively to each other at a high speed.

2. The process of treating materials in a gaseous or finely divided state which consists in mixing a plurality of the materials 35 and in submitting the mixed materials to the action of high tension electricity in a receiver in which a pair of electrodes are moved relatively to each other at a high speed.

3. The process of treating materials in a gaseous or finely divided state which consists in mixing two or more of the materials 45 under heat, and in submitting the mixed materials to the action of high tension electricity in a receiver in which a pair of electrodes are moved relatively to each other at a high speed.

50 4. The process of treating materials in a gaseous or finely divided state which consists in mixing the materials with a reducing agent and in submitting the mixed materials to the action of high tension electricity in a receiver in which a pair of electrodes are moved relatively to each other at a high speed.

55 5. The process of treating materials in a gaseous or finely divided state which consists in mixing a plurality of the materials in proportions which vary according to the products which it is desired to obtain and in submitting such mixed materials to the action of high tension electricity in a receiver in which a pair of electrodes are

moved relatively to each other at a high speed.

6. The process of treating materials in a gaseous or finely divided state which consists in submitting such materials at low 70 pressure to the action of high tension electricity in a receiver in which a pair of electrodes are moved relatively to each other at a high speed.

7. The process of treating hydrocarbon 75 gas which consists in submitting the gas to the action of high tension electricity in a receiver in which a pair of electrodes are moved relatively to each other at a high speed. 80

8. The process of treating materials in a gaseous or finely divided state which consists in submitting such materials to the action of a high tension electricity in a receiver in which a pair of electrodes are 85 moved relatively to each other at a high speed and in varying the relative speeds of such electrode so as to control the resulting products.

9. The process of treating materials in a gaseous or finely divided state which consists in submitting such materials to the action of high tension electricity in a receiver in which a pair of electrodes are 90 moved relatively to each other at a high speed, and in varying the relative speed of such electrodes and the tension of the electricity so as to control the resulting products. 95

10. A process for treating materials in a gaseous or finely divided state which consists in heating said materials and in submitting the materials in their heated state 100 to the action of high tension electricity.

11. A process for treating materials in a gaseous or finely divided state which consists in heating said materials and in submitting the materials in their heated state 105 to the action of high tension electricity by passing electrically charged particles through the material. 110

12. A process for producing hydrocarbon gas consisting in passing a material containing carbon or hydrocarbons successively through all hotter regions of a furnace, partially heated by electrical heating devices arranged adjacent the extreme region of the furnace, taking off the hydrocarbon gases produced in the furnaces at a plurality of different regions of the furnace and bringing the vapors taken out from the 115 different regions together. 120

13. A process for producing and treating hydrocarbon gas which consists in passing a material containing carbon or hydrocarbon 125 successively through all hotter regions of a furnace, partially heated by electrical heating devices arranged adjacent the extreme region of the furnace, taking off the hydrocarbon gases produced in the furnaces at a plurality of different regions of the 130

- 4
- furnace and bringing the vapors taken out from the different regions together and submitting such gases to the action of high tension electricity.
- 5 14. A process for producing and treating hydrocarbon gas which consists in passing a material containing carbon or hydrocarbons successively through all hotter regions of a furnace, partially heated by electrical heating devices arranged adjacent the extreme region of the furnace, taking off the hydrocarbon gases produced in the furnaces at a plurality of different regions of the furnace and bringing the vapors taken out
- 10 15 from the different regions together and submitting such gases to the action of high tension electricity, in a receiver in which a pair of electrodes are moved relatively to each other at a high speed.
- 20 16. A process of treating hydrocarbon gas which consists in mixing such gas with other materials in a gaseous or finely divided state and in submitting such mixed materials to the action of high tension electricity.
- 25 17. A process of treating hydrocarbon gas which consists in mixing such gas with a metal in a finely divided state and in submitting such mixed materials to the action of high tension electricity.
- 30 18. Apparatus for carrying out the process as claimed in claim 1 comprising a receiver, electrodes within such receiver connected to a source of high tension electricity and means for moving said electrodes relatively to each other at a high speed so as to produce electric waves of predetermined shape within said receiver.
- 35 19. Apparatus for carrying out the process as claimed in claim 1 comprising a receiver, a pair of electrodes within such receiver connected to a source of high tension electricity, one of such electrodes having a plurality of thin arms extending therefrom and the other of such electrodes comprising a pair of upstanding arms one on each side of said first mentioned electrode, and means for moving said electrodes relatively to each other.
- 40 20. Apparatus as claimed in claim 19 characterized in that one of said electrodes is connected to a condenser.
- 45 21. An apparatus as claimed in claim 19 characterized in that the means for moving said electrodes relatively to each other comprises means for effecting the rotation of such electrodes.
- 50 22. An apparatus as claimed in claim 19 characterized in that the receiver is made of insulating material.
- 55 23. An apparatus as claimed in claim 22 characterized in that a second receiver surrounds the first receiver and is spaced therefrom thus forming an annular chamber about such first receiver and that an inlet and an outlet is provided to and from such annular chamber in such manner that the material first passes through such annular chamber and is subsequently directed into the inner receiver.
- 60 24. Apparatus as claimed in claim 19 characterized in that the two arms of the second electrode are adapted to rotate in adjacent proximity to the inner surface of the receiver thus effecting the cleaning of the said inner surface.
- 65 25. Apparatus as claimed in claim 24 characterized by the provision of a conveyer arranged to continuously discharge solid and viscous matter accumulating at the bottom of the apparatus.
- 70 26. Apparatus for carrying out the process as claimed in claim 14 comprising in combination a vertical furnace having an open bottom, a feeding device arranged at the top of the furnace, an electric heating device arranged below the furnace, a receiver for the hydrocarbon gases produced in said furnace, means for passing such gases into said receiver, electrodes within such receiver connected to a source of high tension electricity and means for moving said electrodes relatively to each other at a high speed so as to produce electric waves of predetermined shape within such receiver.
- 75 27. Apparatus as claimed in claim 26 characterized by the provision of a masonry structure surrounding the furnace and provided with channels adapted to be connected with a source of heated fluid and so arranged as to cause the heated fluid to flow in a direction opposite to that of the material fed to the furnace.
- 80 28. Apparatus as claimed in claim 26 characterized by the provision of a plurality of shelves arranged in stepped relation in the furnace and rotatable brushes associated with such shelves and operable to brush the material from one shelf to the next adjacent lower shelf.
